UNITED STATES PATENT OFFICE.

JOEL G. KIRCHHOFER, OF CHICAGO, ILLINOIS.

CUFF-HOLDER.

SPECIFICATION forming part of Letters Patent No. 662,197, dated November 20, 1900.

Application filed July 9, 1900. Serial No. 22,908. (No model.)

To all whom it may concern:

Be it known that I, JOEL G. KIRCHHOFER, a citizen of the United States, residing at Chicago, in the county of Cook, in the State of Illinois, have invented certain new and useful Improvements in Cuff-Holders; and I do hereby declare that the following is a full, clear, and exact description of the invention, which will enable others skilled in the art to 10 which it appertains to make and use the same, reference being had to the accompanying drawings, which form part of this specification.

My invention relates to improvements in 15 cuff-holders.

The object of my present invention is to provide a cheap, simple, and economical device for firmly and conveniently securing the cuffs to the coat-sleeve instead of to the shirt-sleeve for the purpose of insuring a proper 20 adjustment of the cuffs relative to the coat-sleeves under all conditions of use.

My improvement consists of a pair of pivoted spring-pressed jaws adapted for an 25 interlocking engagement at their rear ends to hold the jaws temporarily open and provided upon their lower face with a pivoted tongue or holding device for securing my improvement to the outer face of the cuffs.

30 In the accompanying drawings of my invention similar reference-numerals indicate like parts throughout the several views, in which—

Figure 1 is a perspective view of my invention in position on the cuff, partly broken 35 away, and showing the buttonhole in which the holding device is secured. Fig. 2 is a plan view of my improvement with the jaws closed and showing in dotted outline the relative position of the jaws when they are open and also shows in dotted outline the cuff-holder tongue extended. Fig. 3 is a bottom plan of the same with the jaws shown in their 40 open position and in dotted outline in their closed position. Fig. 4 is a side view of the same, broken away in part to show the actuating coil-spring. Fig. 5 is a front end view of the same with the jaws open, showing the coil-spring and the lateral guide for the 45 movable jaw. Fig. 6 is a bottom plan broken away to show a lateral flange on the fixed jaw,

which prevents all danger of cutting the cuff in use.

My improvement is preferably stamped, cut, or pressed from sheet metal in three parts or 55 pieces—viz, the two jaws with their integral interlocking parts and the pivoted fastening-tongue hereinafter described.

The jaw 1 is provided upon both its upper and lower sides with the apertured ears 2 and 60 3, respectively, in which a pin 4 is secured, on which is arranged a coil-spring 5, having its free ends bearing against the opposite inner faces of the two coacting jaws, respectively, whereby the holding-jaws are held 65 open against the tension of the said spring. The rear end of the jaw 1 is provided with an integral looped spring 6, Figs. 2 and 3, having upon its free end a hook 7, adapted to form a holding engagement with the interlocking end of the other jaw when the jaws are held open. The apertured ear 3 has a forwardly-extended lateral lug 8, which is interposed between the cuff and the jaw 9 to prevent any wearing or tearing contact with 70 the cuff in the lateral movement of the said jaw 9. The said ear 3 is also provided with a downwardly-bent and forwardly-extended lug 10, to whose forward end is pivoted a plate 11, which serves to secure the device 75 firmly upon the cuff 12 in the manner hereinafter described. The said co-operating jaw 9 has a pair of apertured ears 13 and 14, through which the said pivot-pin 4 passes, and has upon its rear end a hook 15, adapted to form 80 a holding engagement with the said hook 7, Fig. 3. The jaw 1 is also provided upon its forward lower edge with a longitudinal inwardly-turned flange 16, Fig. 6, constituting an extension of the adjacent ear 3, and is 85 designed to prevent all danger of tearing the adjacent surface of the cuff in use. The said jaws are of course provided upon their lower forward ends with a series of interlocking teeth, as shown in Fig. 5, adapted to seize 90 and hold to the coat-sleeve lining.

While my device may be made of any suitable sheet metal, it is preferably made of aluminium.

The manner of employing my improvement 100 thus described is obvious and, briefly stated, is as follows: To place my invention in posi-

tion on a cuff, the operator first straightens out the pivoted plate 11 in longitudinal alinement with the said lug 10 and then passes it through the buttonholes of the cuff and is 5 then firmly secured in position, Fig. 1, by rotating plate 11 back into the position shown in dotted outline in Fig. 4. The operator now compresses the rear ends of the holder together until the said hooks 7 and 15 engage, 10 thereby firmly holding the jaws apart until a portion of the coat-sleeve lining, which is of course loose and pliable, is inserted between the said jaws, after which the jaws are sprung together by a slight pressure on the spring- 15 loop 6, thereby disengaging the said hooks 7 and 15. The cuff will now be firmly and securely held at any desired adjustment relative to the coat-sleeve which is desired.

Obviously the mere form of the spring-engaging ends of the said jaws is immaterial and can be variously modified, and the lower edge of both of the said jaws may be provided with an inturned longitudinal flange 16, if desired, for the purpose above specified.

25 Having thus described my invention, what I desire to secure by Letters Patent is—

1. In a cuff-holder the combination of two spring-pressed pivotally-united coöperating holding-jaws normally closed having upon 30 their forward end a series of teeth, and upon

their rear end a pair of spring-hooks adapted for an interlocking engagement for the purpose of holding the said jaws temporarily open; and means for securing the said holder in position on the cuff.

35

2. A cuff-holder consisting of a pair of spring-pressed jaws pivotally united and normally closed, having upon their lower edges a lateral flange adapted to avoid a wearing contact with the cuff, and provided upon their rear end with spring-hooks adapted for an interlocking engagement to hold the said jaws temporarily open; and means for securing the holder in position.

40

3. The combination in a cuff-holder of a pair of spring-pressed jaws pivotally connected and normally closed, one of said jaws being provided upon the lower edge of its forward end with a longitudinal flange for the purpose specified, and also provided with a guiding-flange arranged between the lower edge of the other jaw or movable jaw and the adjacent face of the cuff.

45

Signed by me at Chicago, county of Cook, State of Illinois, this 30th day of June, A. D. 55 1900.

JOEL G. KIRCHHOFER.
